UNITED STATES PATENT OFFICE.

VARTAN BERBERIAN, OF PROVIDENCE, RHODE ISLAND.

DESIGN FOR A BADGE OR SIMILAR ARTICLE.

52,263.

Specification for Design.

Patented Aug. 20, 1918.

Application filed January 3, 1918. Serial No. 210,226. Term of patent 14 years.

To all whom it may concern:

Be it known that I, VARTAN BERBERIAN, a citizen of the United States, residing at Providence, in the county of Providence and State of Rhode Island, have invented a new, original, and ornamental Design for a Badge or Similar Article, of which the following is a specification, reference being had to the accompanying drawings, forming a part thereof.

The figure is a plan view of my design applied to a flag or banner. The lining on the drawing indicates color.

I claim:

The ornamental design for a badge or similar article, as shown.

In testimony whereof I affix my signature.

VARTAN BERBERIAN.
